partners

Application December 3, 1935, Serial No. 52,632

4 Claims. (Cl. 139—416)

Our present invention relates generally to woven fabric, and has particular reference to ornamental fabrics of the "dotted Swiss" variety.

It is a general object of our invention to provide a woven fabric in which an ornamentation composed of dots or spots is produced in a novel and more economical manner.

One customary way, heretofore, of producing an ornamental spot on a plain-woven ground fabric is to employ four rovings or picks interwoven with a series of adjacent warp threads, so that the exposed portions of the rovings define a substantially circular area. This produces what is known in the trade as a "four-pick" dot. Ornamental spots formed of only two rovings or picks have also been attempted, but as a general rule they are unsatisfactory because they pull out too easily.

In accordance with our present invention, a substantially equilateral spot of ornamentation is produced upon a plain-woven ground by the employment of only two rovings, yet the rovings are of such a character and size and are held down in such a manner that the disadvantages heretofore encountered with ordinary "two-pick" dots are entirely avoided. As a result, we are enabled to produce a fabric of the "dotted Swiss" variety, which is in every respect substantially equivalent, in appearance and strength, to the ordinary fabric having "four-pick" dots. The manufacture of the present fabric is, however, far more economical.

One of the features of our invention lies in the employment of a pair of rovings, each of which has a thickness or width which is approximately one-half of the length or width of the spot that is to be produced. Thus, where the fabric is made of cotton, we employ so-called "six-hank" rovings, whereas ordinary practice has heretofore resorted to "twelve-hank" rovings.

We achieve the foregoing objects, and such other objects as may hereinafter appear or be pointed out, in the manner illustratively exemplified in the accompanying drawing, where-

Figure 1 is a plan view of a fragment of an ornamental fabric of the present character;

Figure 2 is a plan view of the region surrounding one dot, this view being greatly enlarged;

Figure 3 is a cross-sectional view taken substantially along the line 3—3 of Figure 2;

Figure 4 is a cross-sectional view taken substantially along the line 4—4 of Figure 2.

The ground fabric is of a plain-weave, and we have applied the reference numeral 10 to the

ground wefts and the reference numeral 11 to the warp threads. In producing the present spot, we interpose between two adjacent ground wefts the two rovings 12 and 13 which are arranged side by side; and, in accordance with our invention, they engage with six adjacent warps wherever a spot is to be formed on the surface of the fabric. In Figure 2, for example, it will be observed that the rovings 12 and 13 engage with the warp threads 14—19 inclusive. The outermost warps, 10 designated by the reference numerals 14 and 19, pass over both rovings and thereby delimit the spot of ornamentation. Beyond these lines, the rovings float on the rear of the fabric, as will be understood by those skilled in the art, until the 15 region of the next spot is reached. In the finished fabric it is usually customary to shear off the rovings on the back of the fabric, so that only the portions defining the spots are left. It is a 20 spot of this shorn character which is illustrated in Figures 2—4.

It will be observed that the penultimate warps 15 and 18 pass under both rovings. These warp threads tend to push the rovings upwardly on the face of the fabric. The innermost warps 25 16 and 17 weave over and under the rovings in alternate relation, and serve to tie the rovings down. It will be observed that the warp thread 16 passes over the roving 12 and under the roving 13; whereas the warp thread 17 passes under the roving 12 and over the roving 13. 30

In accordance with our invention, each of the rovings 12 and 13 is composed of a piece of yarn which has a thickness or width approximately one-half of the length which is exposed between the outermost warps 14 and 19. Where the fabric is composed of cotton, a so-called "six-hank" roving, or its equivalent, is adequate. The spot produced is substantially equilateral, and to the ordinary observer it creates the same impression as the conventional four-pick dot which has heretofore been customarily employed for a fabric of the present type. 40

The manner in which the exposed portions of the rovings are positioned upwardly on the face 45 of the fabric is shown most clearly in Figures 3 and 4; and these figures, together with Figure 2, clearly depict the manner in which the rovings are firmly held in interwoven relationship to the ground fabric. There is no tendency toward, 50 nor likelihood of, loosening the rovings. Each ornamental spot is, therefore, firmly and staunchly held in position.

While the invention is admirably adapted for use in connection with plain-woven fabrics of 55

- the lawn or voile type, nevertheless it will be understood that the invention has equal applicability to other types of fabrics, including those employing fancy weaves such as dobbies and jacquards. Accordingly, where the term "plain-weave ground" is used herein and in the appended claims, it is intended to refer only to the ground fabric immediately surrounding each dot or spot of ornamentation.
- 10 The present ornamentation can be applied to fabrics composed of various types of ground threads, e. g., mixtures of cotton and rayon yarns or spun rayon yarns, rayon twisted or untwisted yarns, acetate twisted or untwisted yarns, and/or 15 linen yarns. Similarly, the rovings can be made of either white or dyed material, of spun rayon, whether dyed, grey, or bleached, and/or of spun acetate material. The latter type of roving would be advantageous for cross-die purposes.
- 20 In general, it will be understood that changes in the details, herein described and illustrated for the purpose of explaining the nature of our invention, may be made by those skilled in the art without departing from the spirit and scope 25 of the invention as expressed in the appended claims. It is, therefore, intended that these details be interpreted as illustrative, and not in a limiting sense.
- Having thus described our invention, and illustrated its use, what we claim as new and desire to secure by Letters Patent is—
- 30 1. An ornamental woven fabric having a plain-weave ground and a figure thereon composed of dots, each dot being formed by only two rovings

arranged side by side between a pair of adjacent ground wefts, said rovings engaging with six adjacent warps, the outermost warps passing over both rovings to delimit the spot, the penultimate warps passing under both rovings to push them upwardly on the face of the fabric, and the innermost warps weaving over and under said rovings in alternate relation to tie the rovings down. 5

2. An ornamental woven fabric as set forth in claim 1, in which each roving is of sufficient 10 cross-sectional area, with respect to the length which is exposed between said outermost warps, so that the exposed portions of the two rovings will conjointly cover a substantially equilateral area. 15

3. An ornamental woven fabric as set forth in claim 1, in which each roving has a width approximately half of the length which is exposed between said outermost warps.

4. An ornamental woven cotton fabric of the 20 voile or lawn type, having a plain-weave ground and a figure thereon composed of dots, each dot being formed by only two approximately six-hank cotton rovings arranged side by side between a pair of adjacent ground wefts, said rovings en- 25 gaging with six adjacent warps, the outermost warps passing over both rovings to delimit the spot, the penultimate warps passing under both rovings to push them upwardly on the face of the fabric, and the innermost warps weaving 30 over and under said rovings in alternate relation to tie the rovings down.

LEWIS HAMER.
